HENRY KNICKMEYER, OF ST. LOUIS, MISSOURI, ASSIGNOR TO SMITH & DAVIS MANUFACTURING COMPANY, OF ST. LOUIS, MISSOURI, A CORPORATION OF MISSOURI.

LINK FABRIC.

1,259,998.

Specification of Letters Patent. Patented Mar. 19, 1918.

Application filed November 3, 1917. Serial No. 200,138.

To all whom it may concern:

Be it known that I, HENRY KNICKMEYER, a citizen of the United States, residing at St. Louis, State of Missouri, have invented 5 certain new and useful Improvements in Link Fabrics, of which the following is a full, clear, and exact description, reference being had to the accompanying drawings, forming a part hereof.

10 The present invention is directed to that class of wire fabrics known as link fabrics, a form of fabric used to a considerable extent for purposes of bed-bottoms. The objects sought by the invention are, to provide 15 a fabric which will be noiseless; one which will not sag or give sidewise; one in which the links will not stretch under normal conditions of service; one in which the links are so jointed to one another as to cause the 20 fabric to readily conform and respond to the shape and movements of the body of the occupant of the bed; one which will be comparatively inexpensive to manufacture containing as it does a minimum number of 25 parts; and one possessing further and other advantages fully apparent from the following detailed description in connection with the accompanying drawings in which—

Figure 1 represents a top plan of a portion 30 of the improved fabric serving the purpose of a bed-bottom; Fig. 2 is an enlarged vertical longitudinal section on the line 2—2 of Fig. 1; Fig. 3 is an enlarged vertical cross-section on the line 3—3 of Fig. 1; Fig. 4 is a top plan of one of the longitudinal links or units detached; Fig. 5 is a side view thereof; Fig. 6 is a vertical longitudinal sectional detail on the line 6—6 of Fig. 4; and Fig. 7 is an enlarged cross-sectional detail on the line 7—7 of Fig. 4.

Referring to the drawings, 1 represents 45 one of the end rails of a bed-bottom frame, said rail in the present instance being in the form of an angle bar, and well understood in the art. Carried by the end rails are helical springs 2 to which the opposite ends of the fabric are secured. The improved fabric comprises a series of parallel rows of longitudinally disposed links or 50 units coupled together in hinged relation, and a series of parallel rows of transverse links coupled to the longitudinal links as more fully hereinafter described. The terms "longitudinal" and "transverse" as here employed are merely relative of course and

are employed for the sake of convenience, the longitudinal links having reference to the links which run lengthwise with the bed where the fabric is used as a bed-bottom, the transverse links being those which run cross-wise of the bed. In other relations the transverse links might become the longitudinal members, and the longitudinal links the transverse members, the purpose of the terms being to bring out the fact that one 60 set of links is transverse to the other set.

In the present embodiment of my invention the longitudinal link is composed of a single piece of wire bent so as to form two arms or limbs 3, 3, terminating at their free 65 ends in downwardly turned hooks or loops 4, 4, the opposite end of the link being formed with a transverse or cross anchor member 5 flanked by the eyes 6, 6, which are disposed exteriorly to the arms 3, 3. The 70 eyes 6, 6, are spaced sufficiently apart to permit the anchoring between the eyes of the hooks 4, 4, of one link to the member 5 of an adjacent link, the anchor members at 75 one end of the fabric being coupled to the 80 springs 2 as shown, the hooks 4, 4, at the opposite end of the fabric being of course coupled to the springs at said end, a matter 85 quite obvious and requiring no illustration. To impart the necessary length to the cross 90 anchor member 5 and the necessary degree of separation to the eyes 6, 6, the wires or 95 arms 3, 3, which are straight and substantially parallel throughout their length, are bent outwardly at 3', the inclined portions 3' connecting the outer portions 3 to the inner or basal substantially parallel portions 3'', each arm being thus formed of inner and outer portions 3, 3'', connected by an intermediate inclined portion 3', the parts 3 and 3'' on the same arm being parallel to one another. The bending of the portions 3' outwardly spaces the basal portions 3'' of opposite arms farther apart than are the outer portions 3, 3. The portions 3'', 3'', form the 100 inner boundaries of the eyes 6, 6, and are spaced sufficiently apart at the points where they cross the member 5 to freely accommodate the hooks 4, 4, of the next succeeding link or unit. As clearly obvious from the 105 drawings, the eyes 6 are formed by a single crossing of the wires, so that at the crossing we have but two thicknesses of wire to contend with, making it easy to dispose the eyes in substantially horizontal planes, that 110

is to say to bring them into the general plane of support of the fabric. It follows therefore that the eyes 6 will be disposed in a horizontal plane whereas the hooks 4 will be disposed in vertical planes. It will be seen (Fig. 4) that the cross anchor member 5 is out of contact with the extreme bends *a* of the arms 3, 3, of the link, the terminals of said member forming the inner boundaries of the eyes 6, 6, and being necessarily disposed between the hooks 4 (or free ends of the arms 3, 3,) and the eyes 6. The eyes may be said to form the base of the link, located as they are at the extreme end thereof. The cross member 5 is somewhat arched or bowed toward the hooks 4 or away from the eyes 6, 6; this arching when a strain or pull is exerted on said member, permitting the member to readily recover when the strain has ceased, this recovery imparting to the fabric the necessary resiliency without danger of the arched members yielding to or past the point of their limit of elasticity so as to cause the fabric to sag. This virtue of preventing a sag would be inherent in a fabric as here constructed even were the arch of the member 5 substantially a flat one between the terminals 3'', 3''. In either case a pull exerted on the anchor member 5 would tend to close the eyes 6, which tendency is resisted by the spring and stiffness of the wire when bent into the formations 5, 6, 6, as shown (or into formations which are their full equivalent) so that a sagging of the fabric is practically impossible under normal conditions of service. The spacing of the cross member 5 from the basal bends *a* of the arms 3, 3, necessarily enhances the resiliency of the link without impairing its resistance to strains. The adjacent eyes 6, 6, of opposed links in the several longitudinal rows are pivotally coupled to the adjacent downwardly turned hooks or loops 7 of the transverse links 8 as shown, the meeting of the members 3, 3, of contiguous links and of the links 8, 8, as described forming not only a flexible and noiseless joint, but a resilient one as well, and at the same time a joint sufficiently stiff to resist sagging. The terminal transverse links 8 are coupled to the side bars 9 the ends of which are secured to the springs 2 as well understood in the art. Necessarily, and considering the purpose which the anchor member 5 subserves, the crossing of the wires must be such as to bring said member below the wires 3'', 3'', that is to say on the bottom of the fabric (or on the side of the hooks 4 and 7), the upper wires 3'', 3'', taking up any vertical per 60 components of the strains to which said anchor member may be subjected. In the

fabric as shown the longitudinal links of the several rows all point in the same direction, but it would not be a departure from my invention to have alternate rows of said links point in the opposite direction. In that event of course each end of the fabric would terminate in a transverse row of eyes 6, 6, alternating with hooks 4, 4, instead of having all the eyes at one end and hooks at the other as illustrated in the drawings. In such reversal of alternate rows of longitudinal links, the cross rows of the links 8 would of course in no wise be affected.

Having described my invention what I claim is:

1. In a fabric of the character described, a link composed of a single piece of wire bent to form two juxtaposed arms having outer substantially parallel portions spaced apart and terminating at their free ends in hooks bent in the same direction in a given plane, the inner portions of the arms being spaced wider apart than the outer portions and bent into terminal eyes disposed exteriorly to said inner portions and in a plane transverse to the plane of the terminal hooks aforesaid, and an anchor member connecting the eyes at their inner boundaries and arched toward the hooks and spaced from the basal bends of the arms, said anchor member crossing the basal and more widely spaced inner portions of the arms on the same side of the link as the terminal hooks aforesaid.

2. In a fabric of the character described, a link composed of a single piece of wire bent to form two juxtaposed arms each having opposite parallel terminal portions and an intermediate outwardly diverging portion inclined to said parallel portions, the free ends of the outer portions terminating in hooks bent in the same direction in a given plane, the inner portions or these on the opposite sides of the inclined portions being bent into terminal eyes disposed exteriorly to said inner portions and in a plane transverse to the plane of the terminal hooks aforesaid, and an anchor member connecting the eyes at their inner boundaries and arched toward the hooks and spaced from the basal bends of the arms, said anchor member crossing the basal and more widely spaced inner portions of the arms on the same side of the link as the terminal hooks aforesaid.

In testimony whereof I affix my signature, in presence of two witnesses.

HENRY KNICKMEYER.
